EXERCISER

Harry L. Hussmann, Los Angeles, Calif.

Application April 12, 1937, Serial No. 136,328

2 Claims. (Cl. 272—57)

This invention relates to an implement for exercising the human foot, both as a means for strengthening the muscles of the foot and for the purpose of correcting certain foot deformities 5 or abnormal conditions.

Among the objects of the invention are to provide a simplified less expensive foot exerciser, and one that will be very durable and easy to use. Also to provide a single article which will be adapted simultaneously to exercise both feet 10 of the user, and which will be constructed in such a manner as to aid the user in keeping his feet out of contact with each other while he is making use of the device to exercise them.

Another object of the invention is to provide 15 an improved article for massaging the soles of the feet while it is being used to exercise the foot muscles.

Still another object of the invention is to provide 20 an improved massaging and exercising article which may be used by an operator on a patient of the human body.

Other objects, advantages and features of the 25 invention may hereinafter appear.

Referring to the accompanying drawing, which 30 illustrates what is at present deemed to be a preferred embodiment of the invention,

Fig. 1 is a side elevation of the device.

Fig. 2 is an end elevation thereof.

Referring in detail to the drawing, the foot-exerciser implement shown consists of an approximately fusiform body 10 surrounded at each end with a rounded ridge 11 and desirably having through it an axial bore or passage 12.

The body portion 10 of the implement is shown 35 having, throughout its mid-length portion, a cylindrical exterior surface 13, and from each end of this surface a frusto-conical area 14 extends to the inner side of the ridge 11 at that end of the implement. The surface 14, however need 40 not be truly frusto-conical, but could, for example, be of a longitudinally concaved or convexed character without departing from the scope of the claimed invention.

The hole 12 through the implement serves to 45 roll the exerciser upon a mandrel, and to lighten its weight, and is partially desirable when a cast metal or other heavy material is used. The implement may, however, be made of wood, or of 50 formed sheet metal.

In using the implement as a foot exerciser the

subject, while occupying a chair or other seat, will place the implement upon the portion of the floor underlying his feet and, while pressing upon the implement with the soles of his feet will roll the implement back and forth upon the floor. 5 In doing this he will place a foot upon each frusto-conical surface 14. The outward taper of each of said surfaces 14 will tend to keep the feet out of contact with each other, while the ridges 11 will keep the feet from sliding off from the ends of the implement. Owing to the transversely rounded character of said ridges they 10 form smooth, comfortable abutments engageable by the outer sides of the feet of the user.

Owing to the fact that the ridges 11 are preferably of a somewhat greater diameter than the intermediate portion of the implement said intermediate portion is kept out of contact with the floor and hence, during the exercise of the feet, does not pick up dust or germs from the floor 15 and transfer the same to the soles of the feet. Furthermore, the circular ridges 11 travel upon the floor and therefore exercise the leg muscles to a greater extent, by necessitating longer leg movements than take place in devices where the 20 roller does not bodily move back and forth when used as an exerciser.

I claim:

1. A foot exerciser consisting solely of an elongated symmetrical body having a central portion 30 of a substantially uniform diameter, there being a uniform decrease in the diameter of said body at each side of said central portion, said decreasing diameter being terminated by a circular ridge portion at each end of said body, the diameter of 35 each of said ridge portions being greater than the diameter of said central portion.

2. A foot exerciser consisting of an elongated body having a substantially cylindrical central portion and outwardly tapering frusto-conical 40 end portions, and having around each end a circular ridge, said body being adapted for being rolled back and forth upon a floor under pressure simultaneously from the soles of both feet of a person in a seated posture, said end ridges 45 being of a greater diameter than the intermediate portion of the implement in order to keep said intermediate portion thereof out of contact with a plane surface upon which the implement is supportable.

HARRY L. HUSSMANN.
